UNITED STATES PATENT OFFICE

NEIL CHARLES McGINNIS, OF MEMPHIS, TENNESSEE, ASSIGNOR TO NEIL C.
McGINNIS, JR., OF MEMPHIS, TENNESSEE

CONVEYER

Application filed January 2, 1929. Serial No. 329,827.

This invention relates to a conveyer for transporting materials from one point to another and for carrying out filling and spreading or leveling operations, and is especially 5 adapted for building levees, filling in rail-ways and the like, and for grading land and roadways, and for the performance of other work of this character.

An important object of the invention is 10 the provision of a conveyer of the indicated character adapted for readily transporting materials, and embodying improvements in construction, to the end that the weight of the load will rest directly on the surface of 15 the ground, so as to reduce wear to the minimum.

Another object is the provision of a conveyer of the indicated character embodying improvements in a construction whereby filling and spreading or leveling operations may be readily carried out, and whereby the material may be deposited, and spread or leveled in layers of varying thicknesses.

Another object of the invention is the provision of a device of the indicated character embodying improved features of construction whereby either end may be coupled or hitched to a tractor or the like, for the purpose of moving it, thus making it unnecessary to turn it around, particularly in cases when materials are loaded from the end thereof farthest from the point where the materials are to be deposited.

Other objects of the invention are the provision of a device of the indicated character which will be comparatively inexpensive of manufacture and up-keep, one which will be rugged to withstand extremely rough handling, and one which will be of simplified 40 construction.

With the foregoing and other objects in view, the invention resides in the combinations, construction and arrangement of the parts hereinafter fully described and illustrated in the accompanying drawings, in which—

Figure 1 is a side view of the conveyer, the shell door being shown closed in full lines, and open in dot and dash lines, and parts 50 of the hoisting rig being shown lowered in

dot and dash lines, as well as being shown raised in full lines.

Fig. 2 is a detail sectional view of parts of the door latching and releasing means, the section being taken on the line 2—2 of 55 Fig. 3.

Fig. 3 is a plan view of the conveyer, a portion of the shell door being broken away to disclose a detail of construction of the shell.

Fig. 4 is a view of the shell, and the means enabling spreading or leveling of the material, as it is being discharged from the shell.

Fig. 5 is a detail sectional view showing 65 the latch which serves to limit the rotation of the shell to a point enabling the hinging of the shell door.

Fig. 6 is a detail sectional view of the door latching and releasing means, the section being taken on the line 6—6 of Fig. 7.

Fig. 7 is a fragmentary plan view illustrating certain features of the door latching and releasing means.

Fig. 8 is a detail sectional view taken on the line 8—8 of Fig. 9.

Fig. 9 is a fragmentary plan view partly in section and illustrating parts of the door hinging means.

Referring now more particularly to the drawings, it will be apparent, that the conveyer or device of the present invention includes a shell 10 which may be of any preferred size and is made preferably of sheet steel, the parts thereof being riveted or welded together. The shell 10 is of cylindrical form and therefore presents a circular or cylindrical wall 11 having an opening 12 the size of which is equal to substantially two-fifths of the area of the wall 11. A shaft 13 extends centrally and longitudinally of the shell 10 and the opposite ends thereof project beyond the opposite ends of the shell. Inside of the shell 10 are arranged and secured strengthening disks or walls 14 and 15, the latter dividing the shell 10 into two compartments; said walls 15 preventing the materials from shifting laterally. The opening 90

12 of the shell 10 is controlled by a door 16 95 of sector shape to conform to the wall 11, and 100

said door is somewhat larger than the opening 12 to present marginal portions 17 and 18 which overlap portions 19 and 20 respectively of the wall 11. Tongues 21 are secured to the edge portion 17 of the door 16 in spaced relationship, and each extend downwardly through an opening 22 in the portion 17, and through an opening 23 in the edge portion 19 of the wall 11, said tongue 10 engaging the under side of the portion 19 when the door is in the closed position, as shown most clearly in Fig. 8. Hubs or sockets 24 are secured to the edge portion 17 of the door, and are disposed respectively at opposite sides of the door in axial alignment for a purpose to appear.

In order to latch the door 16 in a closed position and also to release the door so that it may be swung to an opened position there is provided means presently to be described. A bar 25 is arranged on the edge portion 18 of the door and is guided for sliding movement by guides 26 secured to said portion 18. The bar 25 has limited movement by virtue of shoulders 27 and 28 formed on the bar 25, the shoulders being engageable with the guides 26 in the movement thereof, the shoulders 27 limiting the movement of the bar 25 in one direction and the shoulders 28 limiting the movement of the bar in an opposite direction. The bar 25 has a plurality of equally spaced slots 29. Latch elements 30 are arranged on the portion 18 of the door 16 for turning movement, and are adapted to cooperate with the bar 25. Each element 30 includes a laterally projecting pin 31, and a laterally projecting lug 32. Each element 30 is disposed so that the pin 31 thereof will enter one of the slots 29. The portion 20 of the wall 11 has a slot 33 through which the lug 32 of the related element 30 pass. Use is made of a peavey consisting of a bar 34 the lower end of which is tapered and a hook 35 pivotally connected with the bar 34 near the lower end thereof. The bar 25 has a notch 36, and the adjacent end of the shell 10 has an opening to present a socket 37. The peavey serves for moving the bar 25 in opposite directions for the purpose of latching and releasing the door 16. This is accomplished by entering the lower end of the bar 34 in the socket 37, and entering the hook 35 in the notch 36, whereupon the bar 34 may be manipulated to impart sliding movement to the bar 25. In one position of the bar 25, the lugs 32 of the elements 30 will be in engagement with the portion 20 of the wall 11 and therefore hold the door 16 closed, as shown most clearly in Figs. 6 and 7. When the bar 25 is moved in the direction indicated by the arrow in Fig. 7, the elements 30 will be turned one-quarter of a revolution allowing the lugs 32 to pass through the slots 33. Consequently the door 16 may be swung to the open position.

The conveyor includes a main frame 40 built up of suitable structural elements such as angle or channel irons or tubular members riveted or welded together. The frame has secured thereto bearings 41 respectively at opposite sides in which the opposite ends of the shaft 13 are journaled respectively in order to allow the shell 10 to rotate relatively to the frame. Each end of the frame 10 is provided with suitable means such as a 70 coupler 42 whereby the conveyor may be coupled or hitched to a tractor or other power driven vehicle. Each end of the frame 40 has a prop 43 pivotally connected as at 44 with the frame, there also being provided a jointed brace 45 having one end pivotally connected as at 46 with the prop and the opposite end being pivotally connected as at 47 with the frame. Each prop 43 serves when lowered to hold the related end of the frame 40 elevated, as shown most clearly in Fig. 1. Each prop 43 may be held in the raised position by any suitable means indicated at 48 on the frame.

In order to cooperate with the hubs or 90 sockets 24 on the door 16 to enable it to be swung to the opened and closed positions there are provided threaded elements 49. Each element 49 threads in a hub 50 on a bracket 51 secured to the frame 40. Each element 49 has a trunnion 52 at one end, and the opposite end 53 being square to accommodate a crank for the purpose of turning the element 49. The trunnions 52 of the elements 49 are in axial alignment, and may be 100 entered into the sockets 24 when brought into registry therewith. A latch device comprising a toothed rack 54 on one end of the shell 10 and a pivoted dog 55 on the frame 40 serve to prevent rotation of the shell in each direction, and in fact limit its movement in each direction to a point in which the sockets 24 will be in registry with the trunnions 52, when the dog 55 is in engagement with one of the teeth of the rack 54. It will now be, 110 understood that when the trunnions 52 are entered into the socket 24 the door 16 may be swung to the opened and closed positions.

In order to swing the door 16 to the opened and closed positions there is provided means presently to be described, or any equivalent means. In the present instance said means includes a hoisting rig including a frame 60 pivotally mounted as at 61 on the frame 40. The frame 60 has arranged thereon suitable 120 pulleys 62. A suitably braced support 63 is arranged on the frame 40 and carries near the upper end thereof a bracket 64 on which is mounted a motor 65. The shaft of the motor 65 has secured thereto a drum 66. A cable 67 has one end thereof connected with the drum 66 and is wound on said drum, and also is passed around the pulleys 62, the free end of the cable being provided with a hook 68 for engagement with an eye or ring 69 on 130

the door 16. The frame 60 is held in the raised position by latch members 70, there being one at each side of the frame, and each being pivotally connected as at 71 with the frame and each having a notch 72 which receives a pin or stud 73 on the main frame 40. A suitable guide 74 on the frame 40 cooperates with each latch member 70 to prevent it from swinging beyond certain limits. The latch members 70 when engaged respectively with the pins 73 serve to hold the frame 60 in the raised position for hoisting. The motor may be driven by current derived from storage batteries (not shown). It is also to be understood that any other means may be provided for operating the drum 66. A cradle 75 is arranged on the main frame 40 at one end thereof, and is adapted to support the door 16 when it is detached from the shell 10.

It is to be understood that the door 16 will be held by the cradle 75 detached from the shell 10 while the shell is being loaded with material. After the shell 10 has been loaded the elements 49 are manipulated to enter the trunnions 52 into the sockets 24. The frame 60 is then raised and is held in the raised position by the latch members 70 which are engaged with the pins 73. The hook 68 on the cable is then engaged with the ring 69 on the door 16. The motor 69 is then started which will cause the door 16 to be swung to the closed position. The door 16 may then be latched in the manner explained hereinbefore. By unlatching the door 16 it may be swung to the open position in a similar manner, it being understood that the door swings under its own weight for a part of its travel. It is also to be understood that one or both of the props 43 may be brought into its or their propping position or positions to prevent movement of the main frame 40, it also being understood that the frame 40 in being coupled to a tractor will also contribute to hold the frame 40 against movement.

In order that the shell 10 minus the door 16 may serve as a spreader and leveler of the material leaving the shell, as the conveyer is traveling along the ground there is provided a toothed rack 76 which is secured to one of the end walls of the shell 10. The rack 76 is arcuate and concentric to the axis of rotation of the shell. The teeth of the rack 76 coact with the dog 55 hereinbefore referred to to hold the shell in different positions relatively to the frame, and also prevent the shell from rotating when the conveyer is being moved along the ground. From Fig. 4 it will be apparent that the edge portion 19 of the cylindrical wall 11 serves as a leveling or scraping means, and that the same may be disposed relatively to the surface on which the shell travels, at different elevations. It follows therefore that fills or layers of various thicknesses may be laid by merely adjust-

ing the position of the shell 10. In Fig. 4 the dotted line 77 indicates the thickness of the layer of material being laid with the parts in the relationship shown, and the dotted line 78 indicates the maximum thickness or depth of layer which may be spread or laid. While using the conveyer for spreading and leveling the material, the door will be held by the cradle 75, and the door may remain in the cradle when the conveyer is traveling over the ground with the shell empty.

It is to be understood that the features of the invention are not restricted to the precise arrangement of parts shown and described, as details of construction may be modified and rearranged without departing from the spirit of the invention, the scope of which is limited only by the terms of the appended claims.

I claim:

1. A conveyer having the combination of a draft frame, a freely rotatable material-carrying shell on which said frame is mounted and which travels in contact with the ground, said shell having an opening therein for the purpose of loading material into said shell and for discharging the material therefrom, a separate door, coacting means on said frame and door to hinge the door on the frame for swinging movement to opened and closed positions with respect to said opening, and means to latch the door in the closed position on said shell to be carried thereby when said coacting means is disengaged.

2. A conveyer having the combination of a draft frame, a freely rotatable material-carrying shell on which said frame is mounted and which travels in contact with the ground, said shell having an opening therein for the purpose of loading material into said shell and for discharging the material therefrom, a separate door, means adapted to hinge the door for swinging movement to opened and closed positions with respect to said opening in the shell, said means also being disengageable to allow the door to be separated from said shell, and means to secure said door to said shell to be carried thereby to close the opening in the shell when the latter is loaded.

3. A conveyer as defined in claim 2, and means on said frame to receive and hold the door when it is separated from the shell.

4. A conveyer as defined in claim 2, and means to prevent said shell from rotating when the conveyer is being drawn forwardly, whereby said shell minus the door will serve to spread and level the material as it leaves the opening in said shell in the forward movement of the conveyer.

5. A conveyer as defined in claim 2, and coacting means on said shell and frame to hold said shell in different positions with respect to said frame, and also to prevent

said shell from rotating when the conveyer is being drawn along the ground, whereby said shell minus the door will serve to spread the material and lay it the desired depth as it leaves the opening in said shell in the movement of the conveyer.

6. A conveyer having the combination of a draft frame, a freely rotatable cylindrical shell on which said frame is mounted and which travels in contact with the ground, said shell having an opening in the cylindrical wall thereof, a separate door, means adapted to hinge the door on the frame for movement to opened and closed positions, said means also being disengageable to allow the door to be separated from the shell, and means to latch said door to said shell in the closed position to form a part of said shell and to be carried thereby.

7. A conveyer having the combination of a draft frame, a freely rotatable cylindrical shell on which said frame is mounted and which travels in contact with the ground, said shell having an opening in the cylindrical wall thereof, a separate door, means adapted to hinge the door on the frame for movement to opened and closed positions, said means also being disengageable to allow the door to be separated from the shell, and means on opposite edges of said door engageable with said cylindrical wall to hold said door in the closed position, the means on one edge of the door being manipulatable to disengage the same from said wall to allow the door to be moved to the opened position on said shell to be carried thereby.

8. A conveyer having the combination of a draft frame, a freely rotatable material-carrying shell on which said frame is mounted and which travels in contact with the ground, said shell having an opening therein for the purpose of loading material into said shell and for discharging the material therefrom, means to hold said shell in different positions with respect to said frame, whereby said shell will serve to spread and level the material as it leaves the opening in said shell in the movement of the conveyer, and a removable door for said opening to close the same during rotation of the shell.

9. In a conveyer of the class described, in combination, a shell, a separate door for an opening in the shell, tongues on said door which have ends extending through one edge of the door, and said ends being engageable in openings in the shell to hingedly connect the door with the shell for movement to opened and closed positions with respect to its opening.

10. In a conveyer of the class described, in combination, a shell, a separate door for an opening in the shell, a slideable bar on one edge of said door, latch elements on said door edge adjacent said bar, means to cause the movement of the latch elements to their

latching and unlatching positions by the sliding movement of said bar, and engageable and disengageable means to hingedly connect the door with the shell along its edge opposite said first mentioned edge, the provision and arrangement being such, that the door may be swung and latched in a position to close said opening, and also be unlatched and swung to an opened position and be detached from the shell.

11. In a conveyer of the class described, in combination, a shell, a separate door for an opening in the shell, tongues on said door which have ends extending through one edge of the door, and said ends being engageable in openings in the shell to hingedly connect the door with the shell, and latch means to latch said door to said shell and also to unlatch it therefrom along the edge opposite said first mentioned edge, the provision and arrangement being such, that the door may be swung and latched in a position to close said opening, and also be unlatched and swung to an opened position and be detached from the shell.

NEIL CHARLES McGINNIS.
